Primary Examiner — Michael C Stout*Assistant Examiner* — Olivia B. El-Nemri(74) *Attorney, Agent, or Firm* — Breiner & Breiner, L.L.C.(57) **CLAIM**

The ornamental design for a bottle as shown and described.

DESCRIPTION

FIG. 1 is a front/side perspective view of a first embodiment of a bottle showing my design.

FIG. 2 is a bottom/front/side perspective view of the bottle of FIG. 1.

FIG. 3 is a back/side perspective view of the bottle of FIG. 1.

FIG. 4 is a front view of the bottle of FIG. 1.

FIG. 5 is a back view of the bottle of FIG. 1.

FIG. 6 is a first side view of the bottle of FIG. 1.

FIG. 7 is a second side view of the bottle of FIG. 1.

FIG. 8 is a top view of the bottle of FIG. 1; and,

FIG. 9 is a bottom view of the bottle of FIG. 1.

The broken lines in the figures represent portions of the bottle that form no part of the claimed design.
